[57] CLAIM

The ornamental design for a miter saw, as shown and described.

DESCRIPTION

FIG. 1 is a first perspective view, taken from the front and to the left, of the miter saw of the present invention;

FIG. 2 is second perspective view, taken from the front and to the right, of the invention shown in FIG. 1;

FIG. 3 is a third perspective view, taken from the rear, of the invention shown in FIG. 1;

FIG. 4 is a fourth perspective view, taken from the front and to the left, with the saw unit pivoted downward, of the invention shown in FIG. 1;

FIG. 5 is a front elevational view, with the saw unit pivoted downward, of the invention shown in FIG. 1;

FIG. 6 is a rear elevational view, with the saw unit pivoted downward, of the invention shown in FIG. 1;

FIG. 7 is a top view of the invention shown in FIG. 1; and

FIG. 8 is a bottom view of the invention shown in FIG. 1.

FIG. 9 is a left side perspective view, with the saw unit pivoted downward, of the invention shown in FIG. 1; and,

FIG. 10 is a right side perspective view, with the saw unit pivoted downward, of the invention shown in FIG. 1.

The broken line showing is for illustrative purposes only and forms no part of the claimed design.
